UNITED STATES PATENT OFFICE.

FREDERIC T. DE LONG, OF CHICAGO, ILLINOIS, ASSIGNOR TO CHICAGO RAILWAY EQUIPMENT COMPANY, OF CHICAGO, ILLINOIS, A CORPORATION OF ILLINOIS.

THIRD AND FOURTH POINT SUPPORT FOR BRAKE-BEAMS.

1,278,608.

Specification of Letters Patent. Patented Sept. 10, 1918.

Application filed April 9, 1918. Serial No. 227,510.

To all whom it may concern:

Be it known that I, FREDERIC T. DE LONG, a citizen of the United States, residing at Chicago, Illinois, have invented a certain 5 new and useful Improvement in Third and Fourth Point Supports for Brake-Beams, of which the following is a full, clear, and exact description, such as will enable others skilled in the art to which it appertains to 10 make and use the same, reference being had to the accompanying drawings, forming part of this specification, in which—

Figure 1 is a plan view of my improved support as applied to a spring plank for 15 trucks.

Fig. 2 is a side elevational view of the same.

Fig. 3 is a side elevational view of the support detached.

20 Fig. 4 is a plan view of the same.

Fig. 5 is a sectional view on line 5—5 of Fig. 4.

Fig. 6 is a plan view of a modified form.

25 Fig. 7 is a sectional view on line 7—7 of Fig. 6.

Fig. 8 is a detail view of another modified form of support.

This invention relates to a new and useful improvement in third and fourth point supports for brake beams which possesses the 30 properties of being rigid at its point of connection to the spring plank or other part of the truck to which it is secured and of being flexible at its extremity, or extremities, 35 where it supports the beam.

The object of my present invention is to 40 construct a single support of the character described which possesses the properties of rigidity, safety and flexibility and, according to the forms of my invention illustrated in the accompanying drawings, that portion of the support which is secured to the spring plank and which extends on each side thereof is reinforced by a flange or flanges where- 45 by it is made rigid and coextensive with this rigidity it is a support serving as a safety bar, the reinforced portions thereof extending under the compression member of the beam, as shown in Fig. 2; whereas that portion 50 located at the extremities of the support and which extend beyond the compression member and under the tension member is flattened to form a yielding or flexible support for the inner side of the beam. This 55 flattened portion may, if desired, be pro-

vided with a flange or flanges at its extreme outer end so as to locate the hinge or yielding section of the support close to the rigid safety bar section.

In the drawings, 1 indicates the spring 60 plank of the truck and 2 the compression member of the brake beam, 3 the tension member thereof, and 4 the strut. 5 indicates the wearing shoe of the fourth point support, which wearing shoe in this instance 65 is clamped to the tension member to cooperate with the fourth point support located therebeneath.

It is obvious that where my improved form of support is used in connection with 70 a third point arrangement, this supporting shoe should be located at the center of the beam, being preferably carried by the nose portion of the strut as is well known.

The supporting member or track is com- 75 posed of a rigid medial or attaching portion 6 which may be secured in any suitable manner to the spring plank 1, rivets 7 being shown for this purpose in the accompanying drawings. While I have shown this sup- 80 port as extending on each side of the spring plank and being made of one piece, it is ob- 85 vious that it could be divided at its center, i. e., made in two pieces, the separate parts thereof being attached in any suitable manner to the spring plank of the truck. How- 90 ever the support is made, the attaching por- 95 tion thereof is preferably reinforced by flanges 6^a and if the support is made of pressed steel as indicated in Figs. 3 and 4, 90 its flanges may be bent as is well understood, or if the support is formed with an angle, as shown in Figs. 6 and 7, the depending flange 6^b may be left intact as it was originally formed in rolling the angle. The rigid or 95 reinforced portion of the support extends outwardly some distance from the spring plank and under the compression member of the beam so as to form a safety bar whose function is to prevent the beam from falling 100 in the event that the hangers are lost or dis- 105 connected. The extremity of the support indicated at 6^c in Figs. 1 to 4 inclusive is flattened, this flattened portion being located under the supporting member carried by the tension rod or strut as the case may be with respect to fourth and third point supports, this flattened portion forming a 110 resilient or yielding means sufficiently flexi-

date itself when the brakes are applied due to the wear of the shoe or the wheel.

In Fig. 6 I have shown this portion formed by bending the depending flange 6^b of the angle so that the same will be flush with the horizontal flange of the angle. By providing a flat extremity as shown in Figs. 1 to 6, this non-rigid end is flexible throughout its entire length, but if it is desired to locate the 10 flexible end at one point, say just beyond the rigid safety bar portion of the support, the flange or flanges may be cut away as at 6^d, thus leaving the extremity of the supporting track rigid, while locating the hinged or 15 flexible portion thereof at a single point.

It will be readily understood of course that still other modifications and adaptations of my improved third and fourth point support for brake beams may be made and substituted without departing from the scope and 20 spirit of what I claim to be my invention.

I claim:

1. A one piece support for brake beams comprising a rigid safety bar portion, and a 25 yielding supporting portion for the beam integrally connected to said safety bar portion and forming a continuation thereof.

2. A third or fourth point support for 30 brake beams comprising a reinforced attaching portion extending beyond a part of the

truck to which it is secured so as to provide a comparatively rigid and strong safety bar portion, the extremity of said support being flexible.

3. A third or fourth point support for 35 brake beams comprising a flanged rigid attaching portion forming a safety bar, and a flat yielding supporting portion integrally connected thereto and extending therefrom to support the beam.

4. A third or fourth point support for 40 brake beams comprising a rigid supporting portion extending beyond the part of the truck to which it is secured so as to form a strong safety bar element, the extremity of which 45 safety bar element is continued outwardly to form a yielding supporting portion for the beam.

5. A third or fourth point support for 50 brake beams comprising a reinforced attaching portion and a reinforced supporting portion, said portions being connected together by a flexible section.

In testimony whereof I hereunto affix my signature in the presence of two witnesses, 55 this 1 day of April, 1918.

FREDERIC T. DE LONG.
